UNITED STATES PATENT OFFICE.

ERNEST TOMPKINS, OF TROY, NEW YORK.

THREAD-GUIDE HOLDER.

No. 806,443.

Specification of Letters Patent.

Patented Dec. 5, 1905.

Application filed August 15, 1904. Serial No. 220,832.

To all whom it may concern.

Be it known that I, ERNEST TOMPKINS, of Troy, in the county of Rensselaer and State of New York, have invented certain new and 5 useful Improvements in Thread-Guide Holders; and I hereby declare that the following is a full, clear, and exact description thereof, reference being had to the accompanying drawings, which form part of this specification.

This invention relates to textile machinery, and in particular to circular-knitting machines; and its object is to improve the thread guides or eyes of such machine, so that such guides 15 may be readily adjusted to any desired position, either toward or from the table and also around the table. The guides are also made readily removable without disturbing the rails on which they are supported. Each guide is 20 independent of the others and is held securely in position, cannot swing or drop down, and is not obstructed by the rails or supports to which it is attached.

The invention therefore consists in the novel 25 construction of the thread-guides or thread-eye holders and the supports therefor, as hereinafter claimed; and the accompanying drawings illustrate a construction embodying the various features of the invention as applied to the table of a circular-knitting machine; but I have not attempted to show the 30 knitting mechanism nor the bobbin or spool supports, as these form no part of the present invention and are well known.

35 In said drawings, Figure 1 is a side elevation of one of the thread-eyes or guides and the support therefor attached to the table of a knitting-machine, the latter being indicated in section. Fig. 2 is a detailed section on line 40 2 2, Fig. 1. Fig. 3 is a perspective view of a guide and its bracket detached. Fig. 4 is a detailed plan view showing the guide-supports as arranged underneath the top of an ordinary 45 knitting-machine table and also showing some of the guides attached to said supports.

On opposite sides of the knitting-machine table and below the top thereof I secure bars or "supports," as I shall hereinafter call them, B, which are preferably square or angular in 50 cross-section and extend the entire length of the table and have their ends B' bent around the ends of the table and extending to about the center line thereof, so that the two opposite supports B practically encircle the entire 55 table. These supports B may be connected to studs C by means of screws c. (See Fig. 1.)

The inner ends of studs C are reduced in diameter and threaded and are passed through holes a in the depending side flanges A' of the table. The supports B are thus rigidly secured below the table-top A adjacent to the lower edge of the flanges A', the studs C being secured by nuts C', as shown. On these supports B may be placed any desired number of adjustable and removable brackets D, to 65 which the thread guides or eyes E are attached, as hereinafter explained.

Each bracket D is provided with an upper member D', adapted to overlie the support B, and an under member D'', which underlies the support B, these two members being rigidly connected by a front member or web portion. The upper member D' has a lip d', which is adapted to catch over the rear edge of the support B and prevent the bracket slipping 75 forward off the support. After the bracket is adjusted to the proper position longitudinally of the support B it can be secured by means of a bolt d'', tapped through the lower part D'', as indicated in the drawings. Through this part D'', at one side of the bolt d'', is an opening or aperture d, which extends horizontally below the support B and at right angles to the bolt d''. Through this opening is 80 passed the stem e of the thread guide or eye E, which may be conveniently made of wire, as indicated in the drawings, this particular form of guide being *per se* old.

It will be observed from Fig. 1 of the drawings that the guide E lies in a plane below the 85 support B and the lower edge of the web A' of the table, and this permits the guide E to be adjusted horizontally toward or from the bracket D, so as to bring its eye to any desired position relative to the edge of the table 90 without having to move the support B or the bracket D, and when the guide has been properly adjusted on the bracket D it may be secured by means of the bolt d'', tapped through the side of the bracket, as shown in the drawings.

The bracket D, as shown, has no swinging or rocking motion on the support D; but when bolt d'' is loosened the bracket and attached guide can be adjusted to any desired position 100 longitudinally of the support B, and by sufficiently loosening bolt d'' the entire bracket and guide can be removed from the support B. In practice any desired number of these brackets and guides may be attached to the supports B and can be spaced properly apart by 105 adjusting the brackets laterally on the sup-

ports. Then the guide-eyes can be adjusted properly by loosening the bolt d^3 and slipping their stems through the openings d . In ordinary practice the bobbins (which are arranged below the guides and are not shown in the drawings) are arranged so that it is desirable to have the alternate guides at different distances from the table edge viewed vertically. This adjustment or arrangement of guides is easily obtained by the capability of adjustment afforded by the opening d and bolt d^3 . Any desired number of guides may be used, and their relation and adjustment can be readily changed, as is obvious, and the number of guides employed can be always made to correspond to the number of bobbins. It is unnecessary to remove or adjust the supports B when it is desired to remove or adjust any guide, as it is simply necessary to loosen the bolts d^2 d^3 . In like manner more guides can be added when desired by hooking them onto the supports, as is evident.

In Fig. 4 the guides are shown as adjusted to accommodate an arrangement of two rows of bobbins, (not shown;) but, if desired, all the guide-eyes could be adjusted in alinement in one row, or they can be alined in more than two rows.

My improved guides afford the greatest facility for variation in number and adjustment. Once adjusted they remain permanently and fixedly in their positions without any liability to disarrangement, and each guide is adjustable, attachable, and detachable independently of the others.

While I have described the guides as particularly applied to a knitting-machine, obviously they could be applied to other machines where such guides would be useful—as, for example, to bobbin-winding and spooling machines.

I do not wish to restrict myself to the specific form of supports, brackets, and guides

shown in the drawings, as these could be varied within the scope of my invention as defined in the following claims.

Having thus described my invention, what I claim as new, and desire to secure by Letters Patent, is—

1. The combination of a table, a thread-guide-supporting bar fixedly attached to said table and having its ends bent around the ends thereof, a series of independently-adjustable brackets attached to said bar, and thread-guides having stems passed through apertures or openings in the brackets below the plane of the supporting-bar, whereby the guide-eyes are adjustable toward or from the bar, and means for locking said guides when adjusted. 50

2. The combination with a knitting-machine table, of thread-guide-supporting bars fixedly attached to the sides of said table and having their ends bent around its ends, a series of independently-adjustable brackets, each independently attachable to and detachable from said bars, bolts for locking said brackets when adjusted, adjustable thread-guides having stems passed through openings in the brackets at right angles to the bars, and means for locking said guides when adjusted. 65

3. The combination with a knitting-machine table, of a thread-guide-supporting bar attached to the side thereof and having its ends bent around the ends of the table, the adjustable brackets detachably attached to said support and thread-guides adjustably attached to said brackets in a plane below the supporting-bar. 75

In testimony that I claim the foregoing as my own I affix my signature in presence of two witnesses.

ERNEST TOMPKINS.

In presence of—

WILLIAM JOB,

HARRY C. WILCOX.
